C. W. HUSE,
SUPPLEMENTAL AIR FEEDING MEANS FOR FURNACES, BOILERS, OR STOVES,
APPLICATION FILED MAY 9, 1916.

1,192,428.

Patented July 25, 1916.

UNITED STATES PATENT OFFICE.

CHARLES WESLEY HUSE, OF GARY, INDIANA.

SUPPLEMENTAL AIR-FEEDING MEANS FOR FURNACES, BOILERS, OR STOVES.

1,192,428

Specification of Letters Patent. Patented July 25, 1916.

Application filed May 9, 1916. Serial No. 96,300.

To all whom it may concern:

Be it known that I, CHARLES W. HUSE, residing at Gary, in the county of Lake and State of Indiana, have invented a new and 5 Improved Supplemental Air-Feeding Means for Furnaces, Boilers, or Stoves, of which the following is a specification.

My invention has for its object to provide an improved means for introducing heated 10 air as a combustion effecting medium to the combustion chamber of a stove, boiler or furnace whereby the mingling of preheated air with the gases in combustion is effected with increased and more efficient combustion and 15 consequent saving in fuel consumption.

Another object of my invention is the provision of an improved means, adapted to be used on stoves, boilers and furnaces, that is so designed and is capable of such adjustment, relatively to the fire chamber of the 20 stove, boiler or furnace, that it will effect a more complete smoke consumption, provide a more uniform heating and steadier fire draft and the consequent maintenance of 25 uniform temperature in the apartment and, at the same time, effect an increased ventilation by taking the air to be heated and directed into the fire chamber from the house and delivering it at desired points above the 30 fuel.

With other objects in view that will hereinafter appear, I have provided an improved means for heating air and delivering it into the combustion chamber at the desired points 35 on top of the fuel and which embodies the peculiar features of construction and novel arrangement of parts, all of which will first be described in detail, then be specifically pointed out in the appended claim and illustrated in the accompanying drawings, in 40 which:

Figure 1 is a perspective view, parts being in section of a portion of a furnace with my invention operatively applied. Fig. 2 is a 45 longitudinal section thereof taken substantially on the line 2—2 of Fig. 1. Fig. 3 is a perspective view of the several parts that constitute my invention, the said parts being shown separated.

50 My invention in its practical application is applied either to the body of the stove, furnace or boiler, or set in the door of the fire-box of said stove, boiler or furnace.

In the drawing I have shown my invention as set in the fire door of a furnace and 55 in applying the same to the door 1, the latter

is formed with an opening 2 into which is projected the annular flange 30 of a collar 3. As is best shown in Fig. 1, the flange 30 of the collar is of convexed shape in cross section and it is held to its adjusted position by a pair of clamping rings, an outer one 4 and an inner one 5, each of which has a concaved bearing surface for engaging the convexed flange 30 of the collar 3.

60 6—6 designate clamp bolts and nuts that hold the rings 4 and 5 in tight engagement with the collar flange 30.

65 By reason of connecting the collar 3 to the furnace door, as shown and described, a substantial ball and socket joint connection is provided that allows for directing the collar at any angle desired and at the same time conform to the angle of the fire door or casting of the stove, furnace or boiler to which 70 my improvement may be applied.

7 designates an air pipe or tube that is 75 rotatably and longitudinally movable in the collar 3, the inner end of which is projected into the fire-box and terminates in an elbow 80 shaped ejecting nozzle 70.

8 designates an air intake in the nature of an annular head portion, provided with a dished rear wall 80 that terminates in a tubular extension 80^a adapted to fit and be secured in the outer end of the tube 7 and the 85 said head has a series of air inlets 81 which may or may not have the usual slide plate to regulate the size of the openings.

9 designates a lever arm attached to the 90 head, and projected radially therefrom, and by means of which the air intake or head and the tube 7 can be longitudinally or rotatably shifted in the collar 3.

95 By reason of the peculiar shape of the air tube and the manner in which the same is applied to the furnace, the air that is taken in through the air intake or head is thoroughly heated by contact with the heated tube as it is drawn in through such tube 100 from which, in its preheated condition it passes out onto the top of the fire and mixing with the coal gases thereby forms a more perfect combustion and creating the draft needed to properly maintain the fire.

105 By mounting the air tube for longitudinal and rotary movement relatively to the collar 3, as shown and described, the said tube can be adjusted to deliver the air at any point desired over the fuel, the advantages of such 110 adjustment being apparent since in furnaces and stoves lacking an efficient air draft for

2
complete combustion, the partially consumed matter passes to the outlet flue and is lost, so far as heating is concerned.

By reason of the ball and socket connection for the collar 3, in operatively applying my invention, the collar 3 is first set to the angle desired, necessary to conform to the angle of the fire door or casing, and when it is thus set, the collar is held clamped to the 10 adjusted position by tightly clamping the rings 4 and 5 against it, as before stated, and when thus applied, the air tube can be readily shifted to the point over the fuel where most needed and by the discharge of the pre-heated air at such needed point, a more complete combustion is developed and a consequent relative saving of fuel.

What I claim is:

In a stove, boiler or furnace, the combination with the door or casing and the fire pot; 20 of a collar having a convexed portion projected through the door or casing, the said

collar having its outer end rockably mounted in the said door or casing and means for holding the said collar to its said position 25 relatively to the door, the said means consisting of a pair of opposing clamping rings having concaved bearing surfaces that engage the convexed portion of the collar, one of the said rings engaging the inside and the other of the rings engaging the outside of 30 the door or casing, clamp bolts that pass through the door-casing and the rings, nuts engaging the said bolts for drawing the rings into tight engagement with the convexed portion of the collar whereby to fixedly hold the collar to its adjusted positions, an air intake tube projected through the said collar, said tube having longitudinal and rotatable movement within the collar and having 35 its discharging end formed to eject air onto the top of the fuel in the fire pot.

CHARLES WESLEY HUSE.
